UNITED STATES PATENT OFFICE.

EDWARD W. CARNES, OF CHICAGO, ILLINOIS, ASSIGNOR TO AMERICAN CAN COMPANY, OF NEW YORK, N. Y., A CORPORATION OF NEW JERSEY.

SHEET-METAL RECEPTACLE.

1,044,742.

Specification of Letters Patent.

Patented Nov. 19, 1912.

Application filed August 16, 1911, Serial No. 644,370.

To all whom it may concern:

Be it known that I, EDWARD W. CARNES, a citizen of the United States, residing in Chicago, in the county of Cook and State of Illinois, have invented a new and useful Improvement in Sheet-Metal Receptacles, of which the following is a specification.

This invention relates to improvements for sheet metal receptacles.

10 The invention has for its object the provision of a simple, two piece, sheet metal container, which shall be easy and cheap to manufacture, and which shall be strong and durable, and one which may be easily 15 opened, such as is commonly used for dispensing pastes, salves and other similar materials.

In the drawing forming a part of this specification, Figure 1 is a side elevation of 20 a container embodying my invention. Fig. 2 is a vertical section, taken on the diameter of the can, showing in dotted lines, an instrument, such as a coin or screw driver, illustrating the manner of removing the 25 cover from the body portion. Fig. 3 is a bottom plan view and Fig. 4 is an enlarged, detail, vertical section, showing also, in dotted lines, an instrument for removing the cover from the body.

30 In the drawing, the bottom or body portion of the box is represented generally by the reference A and the cover by B. The bottom portion or body A is composed of a single piece of sheet metal which may be 35 easily drawn and has an inset flat bottom portion 5, an upstanding circular flange 6, said flange 6 being inwardly and concavely curved at its upper end, as shown at 7, said portion 7 being of less diameter than that 40 portion of the flange below the bead 8. The flange 6 is furthermore provided, intermediate its ends, that is, at a point removed from the upper edge of the flange with a circumferentially extending external bead 8, which forms a rest or support for the 45 cover B when the same is placed upon the body portion A.

The cover B is provided with a flat top 9 and a downwardly extending cylindrical flange 10. This flange 10, intermediate its ends, that is, above the lower edge of the flange, is provided also with a circumferentially extending external bead 11, which bead is deeper than that shown in the body portion of the can. The lowermost portion

12 of the flange 10 is in alinement with the upper portion of the same, and is adapted to easily slide over and fit the inwardly curved portion 7 of the body portion, yet at the same time it forms a nice, tight fit. 60

In articles of this class, it has heretofore been found difficult to remove the cover from the can, owing to the fact that there is generally no protruding portion which may be engaged by any instrument, such as a 65 coin, screw driver, etc., by which the same may be removed. By providing the external bead 11 on the cover, the same may be easily engaged by any instrument, such as shown in dotted lines at 13, and the same 70 easily removed. Furthermore, by providing the cover and the body with outwardly extending beads, the same are materially strengthened.

I claim:

1. In a sheet metal two-piece container, the combination of a cylindrical body portion having an upwardly extending flange provided with an integral, circumferential, outwardly extending bead removed from the 80 upper edge of the flange, the upper portion of the flange above the bead being concaved inwardly so as to allow of the cover being easily slipped thereover, and a cylindrical cover having a downwardly extending 85 flange provided with an integral, circumferential, outwardly extending bead removed from the lower edge of the flange, the lower portion of the flange fitting over the portion of the body flange above the bead, substantially as specified. 90

2. As an article of manufacture, the combination of a drawn, cylindrical sheet metal body having an inset flat bottom portion and an upwardly extending flange provided 95 with a circumferentially extending external bead below the upper edge of the flange, said bead forming a stop for the cover flange to abut against, the portion of the flange above the bead being of less diameter 100 than the portion of the flange below the bead, and being also inwardly concaved so that the cover may be easily fitted thereover, and a drawn, cylindrical sheet metal cover having a downwardly extending flange 105 adapted to fit over the upper portion of the body flange, and provided with a circumferentially extending external bead removed from the lower edge of the flange, said bead being of greater depth than the bead on 110

the body portion, the diameter of the flange on the cover being the same on either side of the bead, substantially as specified.

3. In a sheet metal receptacle, the combination with the body portion and cover therefor, of a pair of circumferential beads formed respectively on the body and cover a short distance from the edges of the mouths thereof and adapted when the box is

closed to have the edge of a coin inserted ¹⁰ therebetween, the portion of the perimeter of the cover contiguous to its edge forming a collar adapted to make a tight joint with the corresponding part of the body.

EDWARD W. CARNES.
